[57] ABSTRACT

This invention has for its objects the provision of compositions of 6-APA with penicillins since it has been found that 6-APA protects penicillins from the action of β -lactamases produced by many organisms which destroy many types of penicillins.

The 6-APA is provided in a ratio of 1 gram of 6-APA to 20 grams of a given penicillin up to 200 grams of 6-APA to one gram of penicillin.

The penicillin is provided in standard dosages for the particular penicillin employed, and in the usual dosage forms. By penicillin is meant that any acyl derivative of 6-amino-penicillanic acid, including salts, esters and amides thereof. By 6-APA is meant 6-aminopenicillanic acid of which the salts, esters and amides thereof may also be employed.

ENZYME-RESISTANT COMPOSITIONS
CONTAINING PENICILLIN IN COMBINATION
WITH 6-APA

This patent is a continuation of U.S. Pat. No. 613,406, filed Feb. 2, 1967.

This invention relates to novel therapeutic compositions. More particularly, this invention relates to certain antibiotic compositions comprising a penicillin and 6-aminopenicillanic acid (6-APA) or a salt, ester or amide thereof.

The art has long been aware of the problem of resistance on the part of some microorganisms to treatment with penicillin-containing drugs, in many instances, necessitating the search for other therapeutic agents which are effective against these microorganisms.

Such resistance results from the production of enzymes, such as β -lactamase, by such microorganisms which operate to break down the structure of the penicillin molecule and thus destroy its effectiveness.

It has now been discovered that 6-APA can slow down or interfere with the enzymic breakdown of penicillins, particularly with the action of such enzymes as β -lactamases. Thus, microorganisms which are resistant to penicillins by virtue of their production of such enzymes are rendered more susceptible to the action of the penicillins when 6-APA is included in the formulation.

The compositions of this invention are directed against all types of microorganisms which are naturally resistant or become resistant to penicillins by virtue of their ability to produce enzymes which destroy penicillins, particularly the β -lactamases.

The penicillins included within the scope of this invention are any of those which are susceptible to degradation in the presence of the enzymes known as the β -lactamases. More particularly, the penicillins included within the scope of this invention would encompass acids of the formula

wherein X is selected from the group consisting of oxygen and sulfur, and R represents a member selected from the group consisting of aryl, saturated and unsaturated alkyl, aralkyl, alicyclic heterocyclic and substituted derivatives thereof.

More specifically, the aliphatic radicals represented by R include straight-chain, branched-chain, saturated and unsaturated radicals, such radicals containing an interrupting group such as oxygen, sulfur, nitrogen, sulfonyl, as a member of the chain, and those containing one or more of the various substituent groups such as halogen, alkoxy, aryloxy, carbonyl, carboxyl, carboxyamido, carboalkoxy, carboaryloxy, cyano, sulfo, phosphoro, nitro, amino, alkylamino, arylamino, acrylamino, alkyl, acyloxy, acyl, hydroxyl, mercapto, alkyl mercapto, arylmercapto, as well as aryl, heterocyclic and alicyclic and substituted derivatives thereof along the chain. The carbocyclic radicals, that is, the aryl, aralkyl, polycyclic and monocyclic alicyclic radicals, within the ambit of R include fully saturated and partially or completely unsaturated carbocyclic nuclei

and substituted derivatives thereof; e.g., phenyl, naphthyl, phenanthryl, anthryl, styryl, cyclobutyl, 2-methylcyclopentyl, cyclohexyl, α -cyclohexylpropyl, benzyl, naphthylmethyl, decanyl, cyclopentanopolyhydrophenanthryl, and substituted derivatives thereof wherein the substituent or substituents is selected from the group consisting of hydroxy, alkoxy, aryloxy, thiol, thioalkyl, thioaryl, cyano, nitro, carbonyl, acyl, alkyl, aryl, amino, mono- and dialkyl amino, mono- and diaryl amino, carboxyl, carboxamido, mono- and dialkyl carboxamido, mono- and diaryl carboxamido, carboalkoxy, carboaryloxy, sulfonic, phosphoric, carboxyhydrazido and azo. The heterocyclic radicals within the scope of R likewise include the fully saturated and partially or completely unsaturated heterocyclic nuclei, that is, monocyclic and polycyclic or condensed heterocyclic radicals having a 5- or 6-membered ring containing at least one of the hetero atoms oxygen, sulfur, nitrogen, and substituted derivatives thereof. Such heterocyclic radicals include, for example, the monocyclic radicals pyrrol, pyridyl, pyrazinyl, pyrrolidyl, piperidyl, pyrimidinyl, oxazolyl, furyl, thienyl, α -pyranyl, γ -pyranyl, thiazolyl, imidazolyl; the condensed heterocyclic radicals benzofuryl, thionaphthyl, quinolyl, acridyl, isoquinolyl, indolyl, indazolyl, dihydrobenzofuryl, dibenzofuryl, benzimidazolyl, benzoxazolyl, and substituted derivatives thereof. Also included within the scope of this invention are the nontoxic pharmaceutically acceptable esters, amides and salts of the above compound.

The nontoxic, pharmaceutically acceptable salts include metallic salts such as sodium, potassium, calcium and aluminum, the ammonium salt and substituted ammonium salts, e.g., salts of such nontoxic amines as trialkylamines, including triethylamine, procaine, dibenzylamine, N-benzyl- β -phenethylamine, 1-ephedamine, N,N'-dibenzylethylenediamine, dehydroallicetylamine, N,N'-bis-dehydroallicetylethylenediamine, N-(lower-alkyl)piperidines, e.g., N-ethylpiperidine, and other amines which have been used to form salts with benzylpenicillin. The term "(lower)alkyl" as used herein means both straight and branched chain aliphatic hydrocarbon radicals having from one to ten carbon atoms such as methyl, ethyl, propyl, isopropyl, butyl, isobutyl, t-butyl, amyl, hexyl, 2-ethylhexyl, heptyl, decyl, etc.

The esters and amides included within the scope of the present invention are easily hydrolyzed esters and amides which are converted to the free acid form by chemical or enzymatic hydrolysis.

In those cases wherein the penicillin is amphoteric in nature, for instance, ampicillin, this invention also includes salts of such penicillins formed with nontoxic, pharmaceutically acceptable, organic and inorganic acids. Exemplary of such organic salts are those with maleic, fumaric, benzoic, ascorbic, pamoic, succinic, bismethylenesalicylic, methylsulfonic, ethanesulfonic, acetic, propionic, tartaric, salicylic, citric, gluconic, lactic, malic, mandelic, cinnamic, citraconic, aspartic, stearic, plamitic, itaconic, glycolic, p-aminobenzoic, glutamic, benzene sulfonic and theophylline acetic acids as well as the 8-halotheophyllines, for example, 8-chlorotheophylline and 8-bromotheophylline. Exemplary of such inorganic salts are those with hydrochloric, hydrobromic, sulfuric, sulfamic, phosphoric and nitric acids.

Specific penicillins preferred for use in the compositions of this invention include such as benzylpenicillin, α -phenoxypropylpenicillin, 2,6-dimethoxypenicillin, α -phenoxyethylpenicillin, α -aminobenzylpenicillin, 2-biphenylpenicillin, 3-phenyl-5-methylisoxazolepenicillin, 3-(4-chlorophenyl)-5-methylisoxazolepenicillin, 2(2,6-dichlorophenyl)-5-methyloxazolepenicillin, 2-ethoxynaphthylpenicillin, and 3-carboxy-2-quinoxalinecarbonylpenicillin. The nontoxic, pharmaceutically acceptable salts, esters and amides of 6-APA included within the scope of the invention are the same as those recited above in regard to the penicillins of this invention. 6-APA, being amphoteric in nature, will also form the acid-addition salts recited above, and hence, these are also included within the scope of this invention.

Particularly preferred compositions of this invention are those comprising Penicillin G or Ampicillin in combination with 6-aminopenicillanic acid.

The compositions of this invention may be administered so as to provide standard dosages for the particular penicillin employed. In general, such dosages contain from 0.01 to 1.5 grams of the penicillin per kilogram of body weight in combination with sufficient 6-APA to protect the penicillin from the action of the enzyme. The proportion of 6-APA to the penicillin should be from 1-20 to 200-1, more particularly 1-12.5 to 160-1. Particularly preferred proportions of 6-APA to the penicillin are from 1-5 to 5-1.

To illustrate the effect of β -lactamase on benzylpenicillin and the protective effect of the additional presence of 6-APA, the following test procedure is followed.

Sufficient benzylpenicillin is dissolved in distilled water to give a solution containing 12.5 mg. per ml. To a series of 13 $\times$ 100 mm test tubes is added 0.6, 0.4, 0.3 and 0.2 ml. of the penicillin solution. 6-APA is dissolved in 0.4M borate buffer, pH 8.4 to give a solution containing 20 mg./ml. 0.6 ml. of the 6-APA solution is added to each of the above test tubes. To each of these test tubes is then also added 0.1 ml. of a standard commercial penicillinase (β -lactamase) solution containing 50,000 units of enzyme per ml. Finally added to the test tubes is 0.5 ml. of 0.2M phosphate buffer (pH 7.5) and enough water to give a final volume of 2 ml. Thus each test tube contains the following:

TEST TUBE	1	2	3	4
	ml.	mg.	ml.	mg.
Penicillin Solution	0.6	7.5	0.4	5.0
6-APA Solution	0.6	12	0.6	12
β -lactamase Solution	0.1	—	0.1	—
Buffer Solution	0.5	—	0.5	—
Water	0.2	—	0.4	—
Final Volume	2.0	—	2.0	—
Final Concentration				
Penicillin	2.75		2.5	1.88
6-APA	6		6	6.0

The test tubes are placed in a 30°C. water bath for 30 minutes, after which 0.1 ml. of 3N H_2SO_4 is added to stop all enzymatic action. The contents of the test tubes are then extracted with one ml. of n-pentylacetate to

remove the residual penicillin. Filter paper discs, $\frac{1}{8}$ inch, are saturated with the n-pentylacetate solutions and then permitted to air dry. The dry discs are then placed on agar plates seeded with *Staphylococcus aureus* and incubated overnight at 37°C. The zones of inhibition are then measured and the residual active penicillin calculated in the usual fashion against a standard curve obtained with penicillin solutions treated as above except that no 6-APA or enzyme was added. The results obtained are shown in Table I below, wherein the size of the zone of inhibition is taken as 100% in the absence of β -lactamase and 6-APA.

TABLE I

Benzylpenicillin mg./ml.	β -lactamase units	6-APA mg./ml.	Protection of Penicillin G		Residual Active Penicillin (%)

To illustrate the effect of combinations of 6-APA and α -aminobenzylpenicillin on clinically important microorganisms, the following test procedure is employed.

Solutions of the compounds (6-APA and α -aminobenzylpenicillin) are prepared in either trypticase soy broth or penassay broth to give concentrations ranging from 2 to 250 mcg./ml. and 0.1 to 25 mcg./ml., respectively. The test procedure for determining the activity of combinations is generally that described by Oswald et al., "Antibiotic Combinations: An in vitro study of anti-staphylococcal effects of Erythromycin plus penicillin, Streptomycin, or Tetracycline," *Antimicrobial Agents and Chemotherapy* (1961), pp. 904-910.

The results of such experiments are set forth in Table II below, and indicate the advantages of the instant in-

vention, namely that combinations of 6-APA and ampicillin are more active (as shown by reduced minimal inhibitory concentrations [M.K.C.]) than either component alone.

TABLE II

ORGANISM	Effects of Combinations of 6-APA and α -Aminobenzylpenicillin			Combination*

*End point employing minimum concentration of ampicillin.

The compositions provided by the present invention comprise mixtures of a penicillin as provided above in admixture with 6-APA. If desired, this combination may be incorporated with a pharmaceutically acceptable carrier. Further, other therapeutic agents, such as other antibiotics may be included in the compositions of the present invention, for instance, sulfonamides, streptomycin, amphotericin B, nystatin, etc. The compositions may take any of the well-known medicinal dosage forms, e.g., tablets, lozenges, solutions or suspensions.

The following examples illustrate the preparation of 35 various formulations which are encompassed within the scope of the instant invention. The formulations exemplified, however, are not intended to be limitative of the invention since other obvious modifications will occur to one skilled in the art, to which this invention 40 also applies equally.

Example 1

Sodium Ampicillin, sterile	1.0 gms.	30
6-APA, sterile	5.0 gms.	

Aseptically blend the ingredients to provide a dry powder for reconstitution. Fill into sterile vials and seal.

Example 2

Penicillin G Potassium, sterile	5.0 gms.	45
6-APA, sterile	1.0 gms.	

Aseptically blend the powders. Fill into sterile vials at a level of 1 gm./vial of Penicillin G activity.

Example 3

Procaine Penicillin G, sterile	10.0	gms.	50
6-APA, sterile	0.250	gms.	
Sodium citrate	0.750	gms.	
Tween 80	0.030	gms.	
Sodium Carboxymethylcellulose 70M	0.250	gms.	
Water for Injection	q.s.	ml.	
	30.0	ml.	65

Aseptically dissolve the ingredients and add the sterile procaine penicillin G. Stir to homogeneity. Aseptically fill the sterile suspension into vials and seal.

Example 4

Ampicillin trihydrate (sufficient to supply 150 mg. of ampicillin per 5.0 cc. plus a 10% excess)	230.2	gms.
6-APA	46.0	gms.
Saccharin, U.S.P.	7.2	gms.
Sodium Cyclamate	21.6	gms.
Sodium Citrate	18.0	gms.
Sodium Carboxymethylcellulose, low viscosity	7.0	gms.
FD&C Red No. 2	1.5	gms.
Mixed Fruit Flavor, dry	27.0	gms.
Sugar, fine powder, enough to make	2.4	kg.

Make a homogeneous mix of all the powders, sift through a 20 mesh screen and reblend. The powder mixture is filled into glass bottles at the rate of 40 gm. per bottle (sufficient for 12 doses). The suspension is prepared by the pharmacist at the time of dispensing by adding 35 cc. of distilled water, to make a final volume of 60 cc., and shaking. The suspension so prepared is stable for at least seven days when stored in a refrigerator (about 5°C).

Example 5

Penicillin G Potassium (enough to supply 200,000 units of penicillin per 5.0 cc. plus a 10% excess)	124.8	gms.
6-APA	624.0	gms.
Sulfadiazine, U.S.P.	150.0	gms.
Sulfamerazine, U.S.P.	150.0	gms.
Sulfamethazine, U.S.P.	150.0	gms.
Sodium Phosphate, Dibasic, Anhydrous	18.75	gms.
Sodium Phosphate, Monobasic, Anhydrous	18.75	gms.
Saccharin Sodium	2.25	gms.
Sodium Cyclamate	45.0	gms.
Guar Gum	7.5	gms.
FD&C Yellow No. 6	30.0	gms.
Mixed Fruit Flavor, dry	4.0	gms.
Sugar, fine powder, to make	2.4	kg.

Make a homogeneous mix of all the powders, sift through a 20 mesh screen and reblend. The mixture is filled into amber bottles at the rate 80 gm. per bottle

(sufficient for 30 doses). The suspension is prepared by the pharmacist at the time of dispersing by adding 105 cc. of distilled water to make a total volume of 150 cc., and shaking.

Example 6

Penicillin G Potassium (to provide 200,000 units of penicillin) ca.	125.3	mg.
6-APA	250.6	mg.
Chalk	340.0	mg.
Polyvinylpyrrolidone	45.4	mg.
Talc	27.0	mg.
Magnesium Stearate	6.7	mg.
Corn Starch	25.0	mg.
Lactose Spray Dried U.S.P. q.s. to (ca. 130.0 mg.)	950.0	mg.

Make a homogeneous mix of the penicillin G, 6-APA, chalk, polyvinylpyrrolidone, and corn starch and one half of the magnesium stearate and talc. Slug on a rotary tablet press and reduce the slugs to form a granulation. Add the remainder of the talc and magnesium stearate, and sufficient lactose spray dried U.S.P. to make the batch weight. Compress on a suitable rotary tablet press.

Example 7

Ampicillin trihydrate (to provide 250 mg. + 5% excess)		
6-APA	ca. 300.0	mg.
Magnesium Stearate	ca. 75.0	mg.
Milk Sugar U.S.P. q.s. to (ca. 116.0 mg.)	9.0	mg.
	500.0	mg.

Make a homogeneous mix of the powders and slug on a rotary tablet press. Reduce the slugs to fine powder and fill the material into No. 0 empty capsules on a semi-automatic or automatic capsule filler.

Example 8

Procaine Penicillin, sterile	300.0	mg.
6-APA, sterile	7.5	mg.
Sodium citrate, sterile	20.0	mg.
Sodium Carboxymethylcellulose 70M, sterile	2.0	mg.

Aseptically blend the powders and fill into a one-dose vial for reconstitution. Multiple doses may also be filled into sterile vials.

What is claimed is:

1. A method of protecting penicillin from the action of microorganisms which produce β -lactamase enzymes which destroy penicillin which comprises administering a standard dosage form of the penicillin together with an amount of free 6-aminopenicillanic acid or pharmaceutically acceptable salts, esters and amides thereof, the amount being effective to prevent destruction of the penicillin by β -lactamase enzymes, the amount of penicillin in the dosage form being from about 0.01 to about 1.5 grams per kilogram of body weight.
2. A method according to claim 1 wherein the dosage form is a tablet.
3. A method according to claim 1 wherein the dosage form is a lozenge.
4. A method according to claim 1 wherein the dosage form is a solution.
5. A method according to claim 1 wherein the dosage form is a suspension.
6. A composition comprising a standard dosage form of penicillin together with an amount of free 6-aminopenicillanic acid, or pharmaceutically acceptable

salts, esters or amides thereof wherein the esters or amides are formed by reaction of the carboxyl group of the acid, the amount of 6-aminopenicillanic acid in the composition being effective to prevent destruction of the penicillin by β -lactamase enzymes, the amount of 6-aminopenicillanic acid to penicillin in the dosage form being from about 1-20 to 200-1.

7. A standard dosage form of penicillin according to claim 6 wherein the dosage form is a tablet.
8. A standard dosage form of penicillin according to claim 6 wherein the dosage form is a lozenge.
9. A standard dosage form of penicillin according to claim 6 wherein the dosage form is a solution.
10. A standard dosage form of penicillin according to claim 6 wherein the dosage form is a suspension.
